US00D746602S

(12) **United States Design Patent**
Olson et al.

(10) **Patent No.:** **US D746,602 S**
(45) **Date of Patent:** **** Jan. 5, 2016**

(54) **DISPLAY BASE**

(71) Applicant: **3M INNOVATIVE PROPERTIES COMPANY**, St. Paul, MN (US)

(72) Inventors: **Judd D. Olson**, Deephaven, MN (US);
Thomas W. Floyd, St. Paul, MN (US);
Kevin E. Kinzer, Forest Lake, MN (US);
Stephan A. Hawthorne, St. Paul, MN (US)

(73) Assignee: **3M INNOVATIVE PROPERTIES COMPANY**, St. Paul, MN (US)

(**) Term: **14 Years**

(21) Appl. No.: **29/521,021**

(22) Filed: **Mar. 19, 2015**

(51) LOC (10) Cl. **06-07**

(52) U.S. Cl. **D6/300**
USPC **D6/300**

(58) **Field of Classification Search**

(57) **CLAIM**

The ornamental design for a display base, as shown and described.

DESCRIPTION

FIG. 1 is a perspective view showing the new design for a display base;

FIG. 2 is a front view thereof;

FIG. 3 is a rear view thereof;

FIG. 4 is a right side view thereof, a left side view being a mirror image; and,

FIG. 5 is a top view thereof, a bottom view being a mirror image.

The portions of the display base in FIGS. 1-5 shown in broken lines are included to show features that form no part of the claimed design.

1 Claim, 4 Drawing Sheets
